(57) **CLAIM**

The ornamental design for a display screen with tabbed user interface, as shown and described.

DESCRIPTION

FIG. 1 is a front view of a display screen with tabbed user interface, showing our new design, with the portion of the user interface having a first appearance state;

FIG. 2 is a front view of the display screen with tabbed user interface, having a second appearance state;

FIG. 3 is a front view of the display screen with tabbed user interface, having a third appearance state;

FIG. 4 is a front view of the display screen with tabbed user interface, having a fourth appearance state;

FIG. 5 is a front view of the display screen with tabbed user interface, having a fifth appearance state;

FIG. 6 is a front view of a display screen with tabbed user interface, showing our new design, with the portion of the user interface having a first appearance state;

FIG. 7 is a front view of the display screen with tabbed user interface, having a second appearance state;

FIG. 8 is a front view of the display screen with tabbed user interface, having a third appearance state;

FIG. 9 is a front view of the display screen with tabbed user interface, having a fourth appearance state;

FIG. 10 is a front view of the display screen with tabbed user interface, having a fifth appearance state;

FIG. 11 is a front view of a display screen with tabbed user interface, our new design, with the portion of the user interface having a first appearance state;

FIG. 12 is a front view of the display screen with tabbed user interface, having a second appearance state;

FIG. 13 is a front view of the display screen with tabbed user interface, having a third appearance state;

FIG. 14 is a front view of the display screen with tabbed user interface, having a fourth appearance state; and,

FIG. 15 is a front view of the display screen with tabbed user interface, having a fifth appearance state.

The appearances of the display screens with tabbed user interface are shown by the representative consecutive appearance states in FIGS. 1-5, 6-10, and 11-15, with a sequence of transitions between the appearance states, rendering animations.

The broken line showing of a display screen, windows, and various graphical representations is for illustrative purposes only and forms no part of the claimed design.

The subject matter in this application includes a process or period in which an image changes into another image. This process or period forms no part of the claimed design.

The perimeters of the claimed design and the underlying unclaimed display screen are understood to be flush.

UNITED STATES PATENT AND TRADEMARK OFFICE
CERTIFICATE OF CORRECTION

PATENT NO. : Des. 578,543 S
APPLICATION NO. : 29/278508
DATED : October 14, 2008
INVENTOR(S) : Ulm et al.

Page 1 of 1

It is certified that error appears in the above-identified patent and that said Letters Patent is hereby corrected as shown below:

On the Title page, Item (57), under "CLAIM", in column 1, lines 1-2, in Claim, after "design for a" delete "display screen with tabbed user interface" and insert -- user interface for a display screen --, therefor.

On the Title page, Item (57) Fig. 11, under "DESCRIPTION", in column 2, line 17, after "interface," insert -- showing --.

On the Title Page, Item (57) Fig. 1A, under "DESCRIPTION", in column 2, line 24, after "and" delete ",".

On the Title Page, Item (57), under "DESCRIPTION", in column 2, line 29, after "states" delete ",".

Signed and Sealed this

Seventeenth Day of February, 2009

JOHN DOLL
Acting Director of the United States Patent and Trademark Office
